CLAIM

The ornamental design for a suction probe control aperture, as shown and described.

DESCRIPTION

FIG. 1 is as isometric view thereof;

FIG. 2 is a top plan view thereof;

FIG. 3 is a bottom plan view thereof;

FIG. 4 is a right side elevation view thereof;

FIG. 5 is a left side elevation view thereof;

FIG. 6 is a rear, end, elevation view thereof;

FIG. 7 is front, end, elevation view thereof;

FIG. 8 is a rear, end, elevation, cross-sectional view taken along line 8-8 of FIG. 2; and,

FIG. 9 is a right, side elevation, cross-sectional view taken along line 9-9 of FIG. 2, absent the temporary central rod used for bending.

The broken line showing of suction probe control aperture is for the purpose of illustrating environmental structure and forms no part of the claimed design.

1 Claim, 3 Drawing Sheets
